UNITED STATES PATENT OFFICE

LESLIE E. LINDGARD, OF SEATTLE, WASHINGTON

MANIKIN TOY

Application filed December 26, 1930. Serial No. 504,967.

This invention is directed to a toy designed to be operated by a person, and represents a boxing match.

The purpose of this invention is to provide a toy which will be cheap to manufacture and which will afford amusement and enjoyment to all who use it.

An object of the invention is to provide a toy which is adapted to be operated by two persons acting in opposition to each other, each controlling the movements of one of the boxers.

A further object of the invention is to provide a toy which will simulate a pair of boxers whose movements are under the direct control of the operators.

A still further object is to provide such an operating element which requires no particular skill or adroitness which is so necessary in the usual operation of manikins and one which a child with a little practice may operate with all the ease of an adult.

A still further object is to provide an operating mechanism in which a separate key is provided for the movement of each part of the boxers rather than depending on the haphazard movement of the arms and legs due to movement of the body.

In the drawings:—

Figure 1 is a perspective view.

Figure 2 is a section on line 2—2 of Figure 1.

Figure 3 is a detail view of one of the figures showing the arm connections.

Figure 4 is a section on line 4—4 of Figure 1.

Figure 5 is a detail view of the mechanism.

The invention is designed as a toy and comprises a platform or ring 11 having posts 12 at the corners connected by ropes 13 in imitation of an ordinary boxing ring.

The boxers 14 and 15 are positioned in approximately the center of the ring and are supported by rods 16 and 17 which are secured to the feet of the figures. The rods 16 and 17 are supported on a bell crank 18 having a tubular sleeve 19 and mounted on a fixed pivot 20. The arm 21 of the bell crank 18 has pivotally secured to one end an operat-

ing rod 22 which projects through the platform 11 and terminates in a button 23. A short projection or arm 24 integral with the operating rod 22 carries a spring 25 which is secured to the operating box 26 at 27.

By means of the push button, the bell crank is turned on its fixed pivot 20 and thereby moves the figures back and forth in an arc 28, thereby allowing the figures to be moved in and out of reach of each other. The mechanism for one of the figures is identical with that of the other and the detailed description for one is thought sufficient. Figure 14 is operated by button 24 and figure 15 by button 23.

The figures are provided with arms 25 which are carried on an axle 26 formed with a crank portion 27. Pivotally secured to the crank portion is a rod 28 which is guided by the tubular sleeve portion 19 of the bell crank 18. The rod 28 passes through an arc-shaped support 29 and is retained in relationship with the support by an upper washer 30 and a lower washer 31, the upper washer supporting the rod and the lower washer preventing its escape from the support 29. The arc-shaped support is formed similar to the arcuate opening 28 and is positioned directly below it. Said support is provided with arms 32 and 33 which are integral with the rocking bar 34. The rocking bar 34 is rotatively mounted on the fixed pivot 35 but limited in its rotation to the length of the crank 27 and the crank 36 to a very slight oscillation, the crank 36 being connected to the free end of the rocking bar at 37. A crank rod 38 carries the crank 36 and a crank handle 39 which is oscillated to move the bar 34 about its pivot 35 which moves the arc-shaped support 29, imparting a vertical motion to the rod 28, causing the arms 25 carrying the boxing gloves 40 to swing on the axle 26. A similar crank handle 41 is similarly connected by mechanism to the figure 14.

In operation, the toy is operated by two persons or players, each operating one figure. By pressing the buttons 23 and 24, the figures are caused to move in an arc coming within reach of one another at portions of the arc and allowing either to be withdrawn.

from reach of the other. At appropriate times the crank handles 39 and 40 are rocked, causing the arms to move and the figures to strike each other as boxers.

- 5 A toy as above described would afford much amusement and enjoyment and could be easily and cheaply produced.

I claim:—

1. A toy comprising a platform having 10 arcuate-shaped openings therein, figures carried above said platform, supports for said figures extending through said openings, means for moving said supports through the paths of the arcuate-shaped openings to move 15 the figures into and out of engagement with each other, and means for moving the arms of each of said figures to strike the opposing figure.

2. A platform formed with arcuate-shaped 20 openings, figures having movable arms arranged on the platform, rods for operating the arms extended through said openings, means below the platform for moving said figures in the path of said arcuate-shaped openings, and means for operating said rods, said latter means including an element providing movement of said rods in accordance with movement of the figures in said arcuate-shaped openings without interfering with the 30 operation of said rods for the arm control.

3. A platform formed with arcuate-shaped 25 openings, figures having movable arms arranged on the platform, rods for operating the arms, said rods extended through said 35 openings, means below the platform for moving said figures in the path of said arcuate-shaped openings, an arc-shaped support for said rods, said support allowing movement of the rods in the path of the arcuate-shaped 40 openings, means for rocking said arc-shaped support whereby movement is imparted to the arm operating rods.

In testimony whereof I affix my signature.
LESLIE E. LINDGARD.
